CIRCULAR FREE STANDING FIREPLACE

Gerald L. Jonas, San Francisco, Calif., assignor to Fire Drum Corporation, San Francisco, Calif., a corporation of California

Filed May 28, 1965, Ser. No. 85,496

Term of patent 14 years

(Cl. D81—7)

FIG. 1

FIG. 4

FIG. 2

FIG. 5

FIGURE 5 is a perspective view of the circular free standing fireplace also showing my new design.

I claim:

The ornamental design for the circular free standing fireplace, as shown.
